UNITED STATES PATENT OFFICE

HENRY GOODFRIEND, OF CHICAGO, ILLINOIS, ASSIGNOR TO MUTUAL METAL MANUFACTURING COMPANY, OF CHICAGO, ILLINOIS, A CORPORATION OF ILLINOIS

DESIGN FOR A LIGHTING-FIXTURE CANOPY OR THE LIKE

Application filed March 31, 1930. Serial No. 35,082. Term of patent 3½ years.

To all whom it may concern:

Be it known that I, HENRY GOODFRIEND, a citizen of the United States, residing at Chicago, in the county of Cook and State of Illinois, have invented a new, original, and ornamental Design for a Lighting-Fixture Canopy or the like, of which the following is a specification, reference being had to the accompanying drawing, forming part thereof.

Fig. 2 is a bottom plan view of the article, a portion of the completed design being shown in solid lines and the remaining portion in broken outline, it being understood that the outlined portion involves a mere repeat of that portion more fully illustrated.

I claim:

The ornamental design for a lighting fixture canopy or the like, as shown and described.

HENRY GOODFRIEND.
